UNITED STATES PATENT OFFICE

163,298

BULLDOZER

Robert G. Le Tourneau, Longview, Tex., assignor
to R. G. Le Tourneau, Inc., Longview, Tex., a
corporation of California

Application December 15, 1948, Serial No. 150,178

Term of patent 14 years

(Cl. D14—3)

To all whom it may concern:

Be it known that I, Robert G. Le Tourneau, a citizen of the United States, residing at Longview, in the county of Gregg, State of Texas, have invented a certain new, original, and ornamental Design for a Bulldozer, of which the following is a specification, reference being had to the accompanying drawing, forming a part thereof.

In the drawing:

Figure 1 is a side view of a bulldozer, showing my new design.

Figure 2 is a front perspective view taken at a slight angle.

Figure 3 is a rear perspective view taken at an angle.

I claim:

The ornamental design for a bulldozer, as shown.

ROBERT G. LE TOURNEAU.
